UNITED STATES PATENT OFFICE

WASHINGTON MEREDITH, OF ADDYSTON, OHIO

MARINE ESCAPE

Application filed January 27, 1930. Serial No. 423,846.

My present invention has reference to a life saving device and is designed for use by the passengers and crew of sunken vessels.

5 The object is the provision of a life saving device that includes water proof compressible sacks that contain therein either oxygen or air and which are designed to be supported on the sides, below the armpits 10 of the user and which have attached to the top portions thereof nipples that are normally closed by valves, together with a waterproof elastic helmet of a particular and peculiar formation which is arranged over 15 the head of the user, which is provided with a window whereby the user can observe outside conditions when on the surface of the water and which has its neck provided with hand operated cocks that are connected by 20 flexible hose connections to the nipples of the sacks and whereby the user by merely pressing his arms against the sacks will cause the air or oxygen to pass into the helmet, which not only insures the free breathing of the 25 user but tends to compress and properly hold the neckband of the helmet against the neck of the user to more effectively insure a water-tight joint and further wherein both sacks and helmet afford buoyant elements 30 which will assist the user in reaching the surface of the water.

To the attainment of the foregoing the invention consists in the improvement hereinafter described and definitely claimed.

35 In the drawings:

Figure 1 is an elevation of the improvement in applied position, the helmet being in section.

Figure 2 is a face view of the helmet.

40 Figure 3 is a sectional view on the line 3-3 of Figure 2.

Figure 4 is a detail sectional view approximately on the line 4-4 of Figure 2.

45 Figure 5 is a plan view of the sack members to better illustrate the harness therefor.

50 As disclosed by the drawings I make use of two compressible but water proof sacks 1, respectively. Each of the sacks, at the top thereof, is formed with a curved de-

pressed portion 2 designed to receive therein in the armpit of the user of the device. There is attached to the inner faces of the sacks longitudinally extending straps 3 which have suitable catch means at their ends for connecting the same. To the upper straps 3 and to the inner faces of the sacks to the opposite sides of the depressions 2 in the sacks there are connected shoulder straps 4. By this arrangement it will be noted that the sacks can be readily arranged over the shoulder and strapped around the torso of the user. The sacks are filled with oxygen or air and the top of each of the sacks is provided with a nipple 5 whose passages are controlled by hand operated valves 6.

The helmet of the improvement is of both elastic and water-proof material, the hood or top thereof being indicated for distinction by the numeral 7. The hood is provided with one or more openings that are covered by transparent plates 8 that afford windows whereby the user of the helmet may observe outside conditions. The hood has its bottom portion formed with a neck or collar extension 9. The collar, at its junction with the hood, is thickened and in the thickened portion there is arranged a split metal ring 10. By reference to Figure 2 of the drawings it will be seen that this ring has its ends inlapping relation and that one of the ends of the ring normally contacts with the shoulder 11 adjacent the second end of the ring for limiting the contraction of the split ring. It will be also noted that the portion of the collar in which thelapping ends of the ring are received is of a greater thickness than that through which the ring passes. The collar has its lower end rounded inwardly and thickened, as at 12, and merges into an upwardly directed neck band 13. This construction permits of the neckband and collar portion of the helmet being expanded so that the same can be readily drawn over the head of the user and when properly positioned on the user the collar will be arranged around the neck of the user and held thereagainst by the split spring band or ring 10.

The collar portion of the helmet, at dia-

metrically opposite points, has fixed thereon hand operated cocks 14, and to these cocks and to the nipples 5 there are connected flexible hose members 15.

5 As far as the description has progressed it will be noted that the improvement may be quickly, easily and securely positioned upon the body and head of the user. Both the helmet and the sacks afford buoyant elements which will assist the user in rising to the surface of the water. When the device is positioned the valves 6 are opened by the user and the cocks 14 are opened to a desired extent. By pressing his arms against the 10 sacks 1 the fluid will flow through the hose members 15 into the helmet. It is to be noted that this fluid is directed against the neck band 13 of the helmet and will thereby exert a gentle pressure against the neck 15 band to force the same against the neck of the user but to an extent which will not cause the said neck band to either inflict injury to or prevent of the free breathing of the user. The air and oxygen let into the 20 water proof and air proof helmet will insure the free breathing of the user for a determined length of time. When the user reaches the surface of the water he can close the valves 6 and detach the hose 15 either 25 from the cocks 14 or from the nipples 5 and thereafter, by regulating the cocks permit atmospheric air entering the helmet. By a simple device of this character it will be apparent that persons submerged can readily 30 raise to the surface of the water and be retained upon said surface for a great length of time even if such persons are not expert swimmers and that their heads will be retained over the surface of the water by the 35 buoyant helmet also for an indefinite length of time or until rescued.

The top of the hood or helmet 7 has centrally let thereinto and firmly secured thereon the stem of a pet cock 16. The pet cock 45 16 is opened to let impure air out of the hood or helmet and the opening of the cock is regulated by the user of the device and, of course, the cock is only opened after the user has reached the surface of the water. 50 While the improvement is primarily designed as a life saving device for buoying persons to the surface of the water the same can be used with equal efficiency by firemen 55 when entering burning and gas charged buildings.

The construction and advantages will, it is thought, be apparent to those skilled in the art to which such invention relates so that further detailed description will not be 60 required. Obviously I do not wish to be restricted to the precise details herein set forth and, therefore, hold myself entitled to make such changes therefrom as fairly fall within the scope of what I claim.

65 Having described the invention, I claim:

1. A device for rescuing persons from sunken marine vessels comprising water proof sacks containing air or oxygen supported under the armpits of a person and having valve controlled nipples, a water and air proof helmet to be arranged over the head of the user having a window therein, and having its collar portion rounded inwardly and thickened and merging into a neck band to be arranged around the neck 70 of the user, cocks secured to the collar portion of the helmet and detachable flexible hose members connecting the cocks with the nipples.

2. A device for rescuing persons from sunken marine vessels comprising water proof sacks containing air or oxygen supported under the armpits of a person and having valve controlled nipples, a water and air proof helmet to be arranged over the 80 head of the user having a window therein, and having its collar portion rounded inwardly and thickened and merging into a neck band to be arranged around the neck 85 of the user, cocks secured to the collar portion of the helmet and detachable flexible hose members connecting the cocks with the nipples, the said collar portion of the helmet having a thickened part, a split spring ring arranged in said thickened part and having lapping ends, and one portion of the ring being offset to afford a shoulder with which the opposite end of the ring contacts for limiting the contraction of the ring.

3. A device for rescuing persons from sunken marine vessels comprising water proof sacks containing air or oxygen supported under the armpits of a person and having valve controlled nipples, a water and air proof helmet to be arranged over the 100 head of the user having a window therein, and having its collar portion rounded inwardly and thickened and merging into a neck band to be arranged around the neck 105 of the user, cocks secured to the collar portion of the helmet and detachable flexible hose members connecting the cocks with the nipples, and a pet cock connected with the top of the helmet.

In testimony whereof I affix my signature. 110
